(57) **CLAIM**

The ornamental design for a skate, as shown and described.

DESCRIPTION

FIG. 1 is a front elevational view of a skate;
FIG. 2 is a rear elevational view thereof;
FIG. 3 is a bottom plan view thereof;
FIG. 4 is a left side elevational view thereof;
FIG. 5 is a front elevational view thereof; and,
FIG. 6 is a front, top, and right side perspective view thereof.
The broken lines in the drawings depict environmental subject matter only and form no part of the claimed design.
The Fila logo forming part of the claimed design is a registered trademark of Fila.
